UNITED STATES PATENT OFFICE

95,079

DESIGN FOR A TEXTILE FABRIC OR SIMILAR ARTICLE OF MANUFACTURE

Albert Schumacher, Passaic, N. J., assignor to Botany Worsted Mills, Passaic, N. J., a corporation of New Jersey

Application February 2, 1935, Serial No. 55,215

Term of patent 14 years

To all whom it may concern:

Be it known that I, Albert Schumacher, a citizen of the United States of America, residing at No. 40 Reid Avenue, in the city of Passaic, State of New Jersey, have invented a new, original, and ornamental Design for a Textile Fabric or Similar Article of Manufacture, of which the following is a specification, reference being had to the accompanying drawing, forming a part thereof in which Fig. 1 shows a face view of a piece of textile fabric embodying my design, while Fig. 2 shows a cross-section on line 2—2 of Fig. 1.

I claim:

The ornamental design for a textile fabric or similar article of manufacture substantially as shown.

ALBERT SCHUMACHER.
